CLAIM

The ornamental design for a traction board, as shown and described.

DESCRIPTION

FIG. 1 is a front perspective view of a traction board showing my new design;

FIG. 2 is a rear perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of FIG. 8;

FIG. 10 is an enlarged view of portion 10 in FIG. 1;

FIG. 11 is an enlarged view of portion 11 in FIG. 1;

FIG. 12 is an enlarged view of portion 12 in FIG. 3;

FIG. 13 is an enlarged view of portion 13 in FIG. 5;

FIG. 14 is an enlarged view of portion 14 in FIG. 1; and,

FIG. 15 is an enlarged view of portion 15 in FIG. 2.
